LOCKING MECHANISM

William J. Landen, Arlington, Va.

Application January 16, 1940, Serial No. 314,099

3 Claims. (Cl. 42—1)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a locking mechanism, applicable, for example, in providing head space adjustment for firearms.

Head space is the measure of the length of the large part of the cartridge chamber, considering the face of the bolt, when locked, as the rear end. Variations from this length is likely to result in malfunctions—if shorter, through failure to breech properly; and if larger, through ruptured cartridge cases. In case of 15 excess head space, even though there be no actual rupture of cases, a terrific pound results, and this is very severe in its effect on the mechanism. If sufficient to cause a rupture, the gun is then completely out of action, as the forward 20 end of the case remains in the chamber after the extracting movement of the bolt and thereby prevents entry of the next cartridge. If the head space is too great but still not enough so as to cause ruptures, the cases will frequently show 25 "incipient ruptures" and "stretches."

25 The purpose of this invention is to provide a simple and easily operable mechanism for establishing correct head space. The invention is characterized by an adjusting screw which serves 30 to fix the longitudinal position of a breech bolt and which is securely held in place by a novel locking arrangement.

35 The specific nature of the invention as well as other objects and advantages thereof will clearly appear from a description of a preferred embodiment as shown in the accompanying drawing in which:

Fig. 1 is a plan view of a breech bolt shown in the closed and locked position;

40 Fig. 2 is a sectional view on the line 2—2 of Fig. 1, and,

Fig. 3 is a sectional view on the line 3—3 of Fig. 2.

45 Referring to the drawing by characters of reference there is shown a rifle bolt comprising a rear handle portion 5 and a front breech closing portion 6. The handle portion 5 includes a lug 7 whose front part has a groove 8 for receiving a coupling flange on the front portion 6 and whose rear face 9 projects laterally to be disposed in front of a locking shoulder 10 on the receiver 11 when the bolt is rotated while in its forward or in-battery position.

50 In the conventional bolt-action rifle the locking shoulder or the rear face 9 of the locking lug is arranged to provide a camming action to facilitate movement of the bolt into locking position. When the bolt is locked the engagement

of the lug and the locking shoulder determine the breech closing position of the front face of the bolt.

5 In order to provide for head space adjustment the locking lug 7 is formed with a longitudinally disposed passage 12 having a reduced threaded bore 13 in its front part and an enlarged smooth bore 14 in its rear part. An adjusting screw 15 having a threaded portion 16 for engagement with the threaded bore 13 is formed with an enlarged head 17 which is disposed in the smooth bore 14. The front end of the screw is provided with a recess 18 for receiving a tool whereby the screw is rotated to longitudinally 10 position the rear face 19 of the head 17. In this 15 invention the face 19 engages the locking shoulder 10 and determines the head space adjustment.

20 The head 17 is formed with an annular row of teeth 20 having the same pitch as the threads 21 of a transversely disposed locking screw 21 which is threaded in the lug. The teeth 20 have a length in excess of the diameter of the locking screw 21 to provide for engagement of screw 21 and teeth 20 over a relatively large range of 25 displacement of the adjusting screw 15.

25 The operation of varying the head space adjustment or allowing for wear of the parts consists in moving the locking screw 21 out of engagement with the adjusting screw 15, rotating 30 the adjusting screw to alter the relative longitudinal position of the face 19 and then re-engaging the locking screw.

35 While the head space adjusting mechanism has been shown mounted in the bolt it is to be understood that it may alternatively be carried by the receiver.

I claim:

1. A breech bolt for a firearm, a projecting locking lug on the bolt, an adjusting screw 40 threaded in the lug and having an end projecting from the lug to provide a surface for establishing head space adjustment for the bolt, and means for locking the adjusting screw in place.

2. A breech bolt for a firearm, a projecting 45 locking lug on the bolt, and an adjusting screw threaded in the lug and having an end projecting from the lug to provide a surface for establishing head space adjustment for the bolt.

3. In a locking mechanism, a support, an adjusting screw threaded in the support and having a projecting portion providing a positioning surface, an annular row of teeth on the adjusting screw, and a locking screw threaded in the support transversely of the adjusting screw and having threads engaging the annular row of teeth 50 on the adjusting screw.

55 WILLIAM J. LANDEN.
